Primary Examiner — Catherine R Oliver-Garcia

(57) **CLAIM**

The ornamental design for handle for holding mobile devices, as shown and described.

DESCRIPTION

FIG. 1 is a front perspective view of a first embodiment of a handle for holding mobile devices showing my new design in an open position;

FIG. 2 is another perspective view shown in a closed position;

FIG. 3 is a perspective view shown in a closed position, and attached to a mobile device;

FIG. 4 is a perspective view of the design, with the finger holder shown open for use;

FIG. 5 is another perspective view shown in use;

FIG. 6 is a perspective view shown in use, with the handle being a support for a mobile device.

FIG. 7 is a front and side perspective view of a second embodiment of the design shown attached to a mobile device;

FIG. 8 is another front and side perspective view of the device shown in a closed position attached to a mobile device;

FIG. 9 is a side perspective view shown in use;

FIG. 10 is a front and side perspective view of a third embodiment of a handle for holding mobile devices showing my new design in a closed position;

FIG. 11 is a front and side perspective view shown in a closed state attached to a mobile device;

FIG. 12 is a front, side perspective view, shown in use in an open state attached to a mobile device;

(Continued)

FIG. 13 is a front and side perspective view shown in use, with the handle being a support for a mobile device;
 FIG. 14 is a perspective view shown in use;
 FIG. 15 is a front and side perspective view of a fourth embodiment of a handle for holding mobile devices showing my new design in an open position; and,
 FIG. 16 is a top, front and side perspective view showing the design in use.
 The broken lines showing of unclaimed mobile devices are included in the drawings for the purpose of illustrating only and form no parts of the claimed design.

1 Claim, 5 Drawing Sheets

Related U.S. Application Data

which is a continuation-in-part of application No. 16/208,986, filed on Dec. 4, 2018, now abandoned.
